UNITED STATES PATENT OFFICE.

KOSSUTH PERPENTE, OF NEW YORK, N. Y.

COLLAR.

SPECIFICATION forming part of Letters Patent No. 292,508, dated February 12, 1884.

Application filed March 22, 1883. (No model.)

To all whom it may concern:

Be it known that I, KOSSUTH PERPENTE, of the city, county, and State of New York, have invented a new and Improved Collar, of 5 which the following is a specification.

Figure 1 represents a face view of my improved collar. Fig. 2 is a cross-section of the same on the line *c c*, Fig. 1. Figs. 3 and 4 are face views of modifications of the collar.

10 This invention relates to an improved standing or other collar, which is so constructed as to overcome the annoyance and difficulty necessitated to pin or otherwise fasten the neck-tie, scarf, or other neck-dressing to the collar, 15 to prevent the same from rising above its proper position or getting into other undesirable shapes.

The invention consists in making the collar out of two or more overlapping pieces, by 20 means of which retaining sections or locks are produced for holding the tie in place.

In the drawings, the letter A represents the upper portion of the collar, and B, Fig. 1, the lower portion. The upper portion laps over 25 the lower portion at the ends *a a*, Fig. 1, and at the center, *b*, and is stitched to the lower portion, where it overlaps it. Between the lines of stitches *a* and *b*, where the two sections of collar are joined together, they are 30 so formed that on the upper part, A, downwardly-projecting sections *d* enter into recesses *e* of the lower part, B. In using the collar these projections *d* will serve to hold the neck-tie or other neck attachment in its proper position, preventing it from slipping or losing 35 its place.

In Fig. 3 is shown a modification of the invention, in that the lines of stitches *b* are vertical, instead of being substantially horizontal, as in Fig. 1, the lower part, B, being in 40 this case made in two pieces.

In Fig. 4 a still other modification is shown, in which the line of stitches *a* is more or less vertical, so as to leave the end button-holes, *e*, in the top part, A, of the collar, instead of 45 in the bottom part, B, as in Fig. 1. In either case the lower section, B, of the collar being stitched to the upper portion, A, by the two series of stitches *a b*, the sections *d* and recesses *e*, for retaining the tie in place, are pro- 50 cedured for practical use.

It would not be practicable, in a linen collar particularly, to cut out the projecting sections *d* without binding them in some manner, which would be very costly and difficult to do, 55 but which is an easy matter to perform before the two parts A and B are joined together; hence the importance of making the collar of the two separate parts.

I do not claim cutting retaining sections out 60 of a collar that is made in one single piece.

I claim—

1. A collar composed of an upper part, A, and of a separate lower part, B, which is overlapped by said part A, the two parts being 65 connected where they overlap by the series of stitches *a b*, and constructed to form the tie-retaining sections *d* and recesses *e* at the places where they do not overlap, substantially as described.

2. A collar constructed of an upper part, A, and a lower part, B, said parts being 70 stitched together where they overlap at *a b*, but disconnected entirely from each other between the rows of stitches, substantially as 75 specified.

KOSSUTH PERPENTE.
